THOMAS W. ROACH, OF SEATTLE, WASHINGTON

SAW FILING GUIDE

Application filed May 4, 1929. Serial No. 360,470.

My invention relates to devices intended for use in filing saws and consists of a guide or indicating device designed for application to a file when used for hand filing a saw, by the use of which the position of the file may be accurately controlled so as to give the saw teeth the proper bevel and inclination of face.

The object of my invention is to provide a simple, dependable and cheap device applicable to a file, and which accurately shows whether the file is properly positioned to secure the right shape of teeth.

My invention consists of a supporting post or frame applicable to a file, upon which is mounted an arm functioning as a plumb and carrying guide arms or fingers occupying angles such that when the device is positioned to bring these guide fingers into parallelism, one with the saw and the other with the file, the file will occupy the proper position relative to the saw.

In the accompanying drawings I have shown my device as applied to the saw and the position thereof relative to the saw, the same being in a preferred type of construction.

Figure 1 is an elevation of the device from the side which is towards the operator.

Figure 2 is a like view, with the device set for giving the side edges of the teeth a chosen angle and showing a short section of a saw.

Figure 3 is an elevation taken from one side of the device.

Figure 4 is a top or plan view illustrating the manner of using the guides which determine the angular position of the axis of the file relative to the plane of the saw.

In principle my invention consists of a plumb attachable to and supported from a file and carrying guide fingers which, when in proper alignment with the saw and with the file, insure that the file is in proper position relative to the saw to produce a tooth having the desired angular flanks and cutting edges. It comprises, also, means for adjusting the support for the plumb to correspond with different angular positions of the teeth flanks.

As a supporting base for the device I em-

ploy a clamp which is mountable upon, and in fixed relation to the file. In the form illustrated this clamp consists of a ring 1 of triangular shape when the device is to be used with a triangular file. A set screw 10, or an equivalent device, secures the clamp upon the handle end of the file.

Carried by the clamp member is a base member 2 upon which is pivotally mounted a post 3, which supports the plumb or bar 4 the latter being suspended from its support 3. The post 3 is pivoted at 30 and preferably carries a pointer 31 located enough to one side of the post to give the operator at all times a clear view thereof. The base member 2 also carries an arcuate scale 20, marked each way from a zero, to facilitate accurate setting of the support or post 3. It is contemplated that there be sufficient friction in the pivot 30 to hold the support in adjusted position.

The post 3 has an upper end 32 extending horizontally and forwardly, and preferably provided with stops or enlargements 33 to retain in proper position the pivotal supporting eyes 40 carried by the forwardly extending horizontal arm 41 of the plumb bar 4. The bar end 32 functions as a guide in a manner which will be later pointed out.

The plumb bar 4 is restrained in its side swinging by an eye 34 carried by the support 3. At its lower end the plumb bar has three guide fingers. Finger 42 should extend forwardly parallel with the axis of the file F. Fingers 43 and 44 extend laterally from the base or inner end of finger 42, at angles relative to finger 42 corresponding with the bevel angle of the edges of the saw teeth. In Figure 4 the finger 43 is parallel with the plane of the saw, indicated by the dotted lines S. This position would be held while filing one side of all teeth, and finger 44 would be then placed parallel with the saw while filing the other sides of the teeth.

In using my device it is secured upon the handle end of the file. The finger 42 should be parallel with the file axis. The support 3 is adjusted so that pointer 31 indicates the angle of inclination of the teeth edges. If the file is put into filing position upon the

saw and rocked into position in which the finger 42 of the plumb is central over the file, the side faces of the saw correspond in angular position with the inclination of the side edges of the teeth. When the fingers 43 or 5 44, as the case may be, are parallel with the plane of the saw, the angular position of the saw axis with relation to the saw is that which will produce the right bevel in the cutting edges of the teeth.

10 In using this device, if the eyes of the operator are focused upon the file, the upper arm 32 will appear as two bars, and if the file be held so that the file is centrally positioned between these two apparent bars, and the bar 42 is central of the file, then the pivot bar 32 is perpendicular over the file, which is the desired position. Actually, the bar 32 and finger 42 are in vertical alignment with each other, and with the file. If the file be 15 tilted sidewise, the pivot 41 which is supported thereon will be thrown to one side or the other, and the finger 42, which must hang vertically below this pivot, is thrown to the same side. Now the three pieces, arm 32, finger 42 and file F, are not in vertical alignment with each other, and it immediately becomes evident that the file is tilted from its proper position, and the filer twists it until the three elements referred to are again in 20 vertical alignment.

25 Placing the filing guide upon the handle end of the file is greatly to be preferred over placing it upon the other end of the file. First, the guide is less in the way and less likely to be injured; second, it is possible to better align the guide with the saw as the guide fingers are for a greater time and more thoroughly between the eye of the operator 30 and the saw; third, inaccuracy caused by a slight twist of the tip section of the file is eliminated.

35 In the present filing guide I have provided for alignment in every necessary direction. The device is simple, inexpensive in construction, is based on correct principles, and enables accurate work being done.

40 What I claim as my invention is:

1. A saw filing guide having an arm swingable transversely of the file, a guide finger alignable with the file and another guide finger alignable with the saw, and both connected to said arm to swing therewith, and means for supporting said swinging arm upon the file.

45 2. A saw filing guide comprising a supporting member and means to secure it in fixed position upon a file, and a guide finger freely swingably supported and pendent from said supporting member, whereby the filer may maintain said finger parallel to the toothed edge of the saw, by keeping the file in proper transverse angular relation to the saw, and regardless of the angular position

50 of the file's working face relative to the edge of a saw tooth.

3. A saw filing guide comprising a post member and means for securing it upon the file, said post adapted to extend upward from 55 the file, a plumb suspended from said post to swing transversely of the file and having a guide finger extending over and parallel with the file, and a pair of other guide fingers extending from opposite sides of the first 60 mentioned guide finger, and at angles thereto corresponding with the angle of filing of the edges of the saw teeth.

4. A saw filing guide including means to secure a file thereto, gravity-controlled 65 means carried by said guide in position to be visually aligned with the file, and means for indicating the angular position of an operating face of the file relative to an edge of a saw tooth.

5. In a saw filing guide the combination with a file holder of an upright post carried by the holder and a plumb suspended from the post and including means adapted to be visually aligned with the file.

6. A saw filing guide having a plumb bar thereon adapted to swing transversely of the file, and a finger extending laterally from the plumb bar, and free to swing therewith above and in substantial parallelism with the file.

7. A saw filing guide comprising a base provided with means to secure engagement with a file, an elevated support carried by said base, an angular scale cooperating with said support to indicate the angular position of an 100 operating face of the file relative to an edge of a saw tooth, and a plumb suspended from said elevated support and including means adapted to be aligned with a file secured to said base.

8. A saw filing guide comprising a base having a socket for receiving a file end, an elevated support carried by said base and adjustable in a plane which is substantially perpendicular to the axis of the file, and a 110 plumb suspended from said elevated support to be aligned with the file.

9. A saw filing guide comprising an upright post, a plumb suspended from the post over the file, and carrying a finger extending 115 therefrom in substantial parallelism with the file, and means for supporting said post from the file and in definite angular relationship to the working face thereof.

10. A saw filing guide having a base including an angle indicating scale adapted to be secured to the file, an upright post pivotally mounted upon said scale and associated therewith to indicate its angular position, and a plumb suspended from said post and 125 adapted to be aligned with the file which is secured to said base.

11. A saw filing guide having a base provided with a socket for receiving a file end, an upstanding angle-indicating scale having a 130

pivot bearing, a post pivotally supported in said bearing and swinging in a plane which is substantially perpendicular to the axis of the file, and a plumb suspended from said post and adapted to be aligned with the file.

12. A saw filing guide having a base provided with a socket for receiving a file end, an upstanding angle-indicating scale having a pivot bearing, a post pivotally supported in said bearing and swinging in a plane which is substantially perpendicular to the axis of the file, and a plumb suspended from said post and adapted to be aligned with the file, said plumb carrying an indicating finger extending over and in the plane of the file.

13. A saw filing guide having a base adapted to be secured to the file, an angle-indicating scale supported on the base, a post pivotally mounted upon said scale and associated therewith, a plumb including a bar suspended from said post and adapted to be aligned with the file which is secured to said base, and a restraining guide extending from the post and provided with a loop enclosing the plumb bar.

Signed at Seattle, Washington, this 27th day of April, 1929.
